(57) **CLAIM**

The ornamental design for a sanitary cover for toilet seat, as shown and described.

DESCRIPTION

FIG. 1 is a perspective view of the sanitary cover for toilet seat showing my design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a plan view showing the state cut in half thereof;

FIG. 9 is a perspective view showing the state used to cut the middle thereof; and,

FIG. 10 is a perspective view showing the folded state to carry thereof.

The broken line showing a toilet is included for the purpose of illustrating environment and forms no part of the claimed design.

The broken lines shown on the claimed design represent fold lines and form part of the claimed design.
